(57) **CLAIM**

The ornamental design for an enclosure, as shown and described.

DESCRIPTION

FIG. 1 is a front left perspective view of the enclosure of the present invention;

FIG. 2 is a front right perspective view thereof;

FIG. 3 is a front view thereof;

FIG. 4 is a left side view thereof;

FIG. 5 is a right side view thereof; and,

FIG. 6 is a top view thereof.

The portions of the figures illustrated in broken lines illustrate portions of the enclosure which form no part of the claimed subject matter.
